ABSTRACT OF THE DISCLOSURE

A garment formed of soft material for the use of patients who have experienced a single mastectomy or a second or a complete mastectomy. The innermost element is in the nature of an undershirt to the front face of which brassiere elements are secured. The rear face fits the patient's back snugly as an undershirt. Secured to the front of this first element is a layer of goods in the nature of a swing on which is mounted the false breastforms attached only at the shoulder, side and arm seams. The outer element or false front concealing the breastforms and brassiere elements is sewed to the above named first element on all sides except the bottom.

This invention relates to brassieres and garments for the use of persons who have suffered the loss of one or both breasts.

It is known that persistent discomfort, even pain, is experienced by such patients when they undertake to hang clothing or brassieres from their shoulders over areas which have been subjected to surgical mastectomy.

Not only does this invention serve to avoid discomfort and pain to the user who has suffered a mastectomy but the improvement more nearly approaches a natural result in both appearance and feel to the end that it provides both comfort and psychological ease of mind for the wearer.

These effects may be understood when the following factors are considered.

It is generally recognized that a surgical operation may leave the patient in a state of mental and physical shock, quite possibly not obvious either to the patient or those associated with the patient. The patient is naturally inclined to reconstruct her physical being and to seek methods of providing brassieres and to fill out brassieres temporarily with such material as sanitary pads and absorbent cotton. It has been suggested that small foam rubber products be used but even such articles do not make up for the gap left by the removal of the ordinary bust line of the well developed woman. As an alternate step, plastic forms filled with liquid have been recommended and in lieu of the latter it has been proposed to use plastic balloon-type brassieres which may be inflated. All such substitutes involve little more than a substitute conventional brassiere.

When a radical mastectomy surgery has been performed, not only is the breast removed but also the muscle area which served to support the breast. The operation leaves the patient with a sunken breast on one side or a gap above the brassiere substitute. In addition, the operation leaves the shoulder and arm areas somewhat tender, and the use of brassiere straps including those of the elastic type frequently cause discomfort analogous to a neuralgic and rheumatic condition.

An active housewife, after a single mastectomy operation, is inclined to go without the services of a brassiere all day while working in order to avoid this shoulder and arm pain, but the resultant effect is not satisfactory because the remaining breast, being without support of the breast which has been removed, becomes painful. The operation has pulled the skin tight against the ribs and

2

it does not "give" or yield with the result that active arm movements create a constant pulling or stretch on the skin and flesh of the remaining breast, especially when that breast is not adequately supported. So an active housewife doing the many activities of her daily duties stands an extremely limited chance of being free of pain. Further, the business of attending to such duties and the feeling of being dependent on her depleted physical being causes a measure of psychological pain.

A patient who has suffered a single mastectomy and subsequently experiences a second or a complete mastectomy runs the full gamut of unfortunate experience as regards discomfort, pain, and the unhappy experience of endeavoring to rebuild her original contours. It is the purpose of the present invention to provide a garment which will avoid discomfort to the wearer and which will, to the largest extent possible, serve to bring back to normal outlines the figure which may have been an element of satisfaction to the patient before her operations.

As a result of the present invention, there is provided a garment of soft material. The innermost element is in the nature of an undershirt, to the front face of which brassiere elements are secured. The rear face hangs down the patient's back. Secured to the front of this first element is a layer of goods in the nature of a swing attached only at the shoulder, side and arm seams. This permits the undergarment with the brassiere features to remain snug to the body. The outer swing element is sewed to the above named first element on all sides except the bottom, thus allowing freedom within the garment and movement without dragging the inner garment away from the body. Preferably the first element which is adapted to fit the patient's body should be of soft nylon tricot. The outer front slip type should likewise be of such soft material although the requirements of a swing covering is not so essentially of such soft material.

With the foregoing features in consideration, the invention will be described in detail and claimed in the following specification and claims when considered in connection with the drawings in which:

FIG. 1 is a side view of a conventional device worn by a patient who has suffered a left single mastectomy showing the loose fit of the shoulder strap;

FIG. 2 is a front view of the patient shown in FIG. 1 illustrating the result often produced when the breast, left for example, and supporting muscle have been removed, showing the characteristic crease in the garment which is not filled out by a conventional brassiere;

FIG. 3 is a front view of the garment shown in FIG. 1 showing the loose fitting at the left shoulder, there being no breast to hold the strap down.

The views illustrated in FIGS. 1, 2 and 3 show faults characteristic of former constructions which are corrected by features disclosed in FIGS. 4 et seq. In short, the views of FIGS. 1, 2 and 3 do not show the improvements provided by this invention.

FIG. 4 shows the front of a completed garment, the front hiding the interior portion and the false breast forms;

FIG. 5 shows the front of the inner garment, also shoulder adjustments with center and side pieces sewed in place for attaching sides of breast forms;

FIG. 6 shows the back and side of the garment shown in FIG. 5 with the side seam set toward the back to allow the breast form to fill in the missing fatty area along the sides and under the arm;

FIG. 7 shows the same structure illustrated in FIG. 6 but with the breast form in place;

FIG. 8 shows a breast form on a liner for plain mastectomy, the extended sides of the liner allowing side to side adjustment of a breast form on a garment;

FIG. 9 shows the same construction for use after a radical mastectomy;

FIG. 10 shows a back view with reinforcing strips on an extension which can be cut off to proper length at the time of being fitted;

FIG. 11 shows a vertical sectional view of a breast form on a liner for use after a radical mastectomy;

FIG. 12 illustrates the difference in the removal of flesh for the plain and radical mastectomies;

FIG. 13 shows how the garment of this invention is adapted to fill in the areas after plain and radical mastectomies;

FIG. 14 shows an inner support brassiere for a remaining breast after a single mastectomy;

FIG. 15 shows how an inner support brassiere fits through the bias cut of the inner front front of the garment, the position of the inner support brassiere being indicated by the dotted line;

FIG. 16 shows an outside view of the inner support brassiere laid out flat;

FIG. 17 shows the support cup which is partially shown in the finished support brassiere, the sling styling providing firm support to the remaining breast; and

FIG. 18 is an inside view showing the bottom of the cup lined with tricot for comfort.

In the foregoing, the various figures of the drawing have been briefly identified. The following detailed description is provided with reference characters designating the different structural details of both the garment and its brassiere features.

It will be understood that FIGS. 1, 2 and 3 show recognized faults of conventional brassiere devices intended to provide assistance for persons who have suffered a single mastectomy and which faults are remedied by the use of the device of this present invention.

Referring to the accompanying drawings, FIG. 4 shows the front 1 of a garment which is intended to be fitted more or less loosely and to hang from shoulder straps. This garment should be made of extremely soft and yielding material such as nylon tricot. The front piece 1 which is in the nature of a slip is secured to the brassiere supporting structure by being sewed at the upper end of the shoulder straps and to the sides as will be explained.

The body engaging portion of this garment is indicated in FIGS. 5, 6 and 7 as comprising a form-fitting garment which may be considered analogous to an undershirt having a front wall 2 and a rear wall 2^a adapted to enclose a patient's bust and upper body portion. This garment 2 and 2^a should be made of the same soft material as is used in the front panel 1. The shoulder straps 3 which join the front panel 2 and the back portion 2^a are fairly broad and are adapted to receive straps 4 extending from whatever brassiere elements are carried by the front panel 2. In FIG. 5 side pieces 5 are sewed in place for attaching the sides of breast forms after shoulder adjustment of the straps is made. Dotted diagonal lines 2^b indicate the approximate position of a bias cut for the reception of either right or left supporting brassiere elements to go through. Such cuts should not be made at the factory but should be postponed until the garment has been bought and the patient fitted with it. Nylon tricot is recognized as not subject to raveling and when cut on the bias presents extremely good resistance to wear. If desired, this front panel 2 may also carry a vertical strip 2^c which may serve for the supplemental attachment of breast forms. It will thus be understood that the panel 2, being the equivalent of the front of an undershirt, supports all of the essential brassiere features. If desired, a slideable fastener 6 may be installed in the back panel 2^a to assist loosening or tightening the garment so that the garment may be readily secured or removed and adapted to conform to the contours of the patient's figure.

It will be observed by reference to FIG. 6 that the side seam is set somewhat toward the back or at least under

the rear side of the upper arm. This is to permit the breast form to fill in the missing fatty area along the sides below the arm. The short slideable fastener 6 shown in FIGS. 6 and 7 may be lined on the inner side for comfort to the wearer.

FIG. 8 shows a form of brassiere breast form 7 mounted with extensible pieces to adapt it for use for a plain mastectomy with the sides of the liner extended to permit side to side adjustment to the breast form. The end pieces 7^a are designed to be secured to the side pieces 5 shown in FIG. 5.

FIG. 9 shows a similar view of a breast form as used after a radical mastectomy.

FIG. 10 shows a back view indicating the outline of a breast form on the forward side of the liner. The extension pieces 7^a at the opposite ends may be cut off to proper length at the time of fitting.

FIG. 12 illustrates the contrasting height and area affected by the surgery of a plain and radical mastectomy.

FIG. 13 illustrates how the garment is applied to the areas treated in the plain and radical mastectomies. The height of the brassiere form is aimed at supplying the filling for the muscle and flesh removed whereby the incomplete area indicated in FIGS. 1, 2 and 3 is built up again and the patient's outer garments will hang properly.

In FIG. 14 there is shown an inner support brassiere for a remaining breast after a single mastectomy. This article is designed to be used under the inner garment which embraces both the front and back of the wearer. The brassiere extends over a single breast and is accompanied by means for securing it to a garment covering the area of the removed breast. The means also has a band 8 extending around the waist and from an upper end adapted to be secured to a strap extending over the shoulder. Said band likewise extends downwardly diagonally across the chest line as at 8^a and terminates below the opposite side of the bust portion in a broadened strap serving as a belt. The strap leads from the upper end of the brassiere and thence passes over the shoulder and extends down the back and is secured to the band 8 around the chest portion to a point behind the back. The foregoing construction is adapted to be mounted under and through the slit in that portion of the garment extending over the front of the bust and next to the skin of the wearer.

In FIG. 15, the bust element has widened the slit such as shown at 2^b in FIG. 5 so that the edges of the slit are indicated at 2^b in FIG. 15.

In FIG. 17 the support cup gives firm support to the remaining breast and this portion of the brassiere is not of tricot. The tricot band is double with a side stretch direction on the outside and the top to bottom stretch on the inside so that the garment will be soft but firm enough not to yield too much and lose its shape. Ordinary elastic wide shoulder strap and side fasteners are used.

This invention provides an inner structure which encloses the bust, front and rear, and to the front face of which brassiere form elements are mounted. This body hugging garment which is of extremely soft yielding material such as nylon tricot is fortified by the use of a front panel also preferably of tricot which is secured at the top and sides to the front panel of the inner garment. In brief, this structure embodies a three fold set of panels secured to each other as described.

The use of the soft natural elasticity of nylon tricot for the garment which embraces the wearer's body and is in direct contact with the skin of the wearer enables it to stay close to the skin during such time as the wearer leans over while wearing a dress cut nearly as low as the garment. There is a tendency at this time for the neck portion of dresses to fall away from the body. This tendency which may disclose the scars of a mastectomy is corrected by the use of the double ply construction of the front with the undergarment hugging

the skin and the outer panel enclosing the front of the undergarment and brassiere fittings. This outer panel is secured to the body hugging undergarment on all sides except the bottom, thus allowing the shape freedom within the garment to move without pulling the inner garment away from the body.

The following optional modification may be put into effect if so desired. In connection with a single mastectomy brassiere, FIG. 14, the cup, reinforcements and strap are not necessarily of tricot on the supporting side. The fabric used may be any sturdy woven nylon, Dacron or cotton since the tricot alone may not give support firm enough to hold the breast in position.

From the foregoing, it will be understood that this invention relates to the use of an improved form of brassiere combined with a garment for use following surgery of either or both breasts, and with or without adjoining muscle areas removed. The completed garment has three separable components, namely, the basic brassiere garment with means for attaching its other two components which comprise either a simulated breast on a liner and a breast supporting article or both right and left simulated breasts on liners.

The simulated breast is sewed to a fabric liner which extends just beyond the simulated breast on either side and the top and having attachments sewed in place on these extensions to correspond with extensions to receive attachments in the basic garment. It will be understood that when two of these forms are used they are attached to each other at the center chest area and to the basic garment at the side and top. When only one of the forms is used it is attached at the top and side with the center fastening common through the center simulated breast extension, the center reinforcing strip of the basic garment and the band of the breast support article being secured after fitting has been made for proper adjustment and alignment of these components.

The following description of the technique in making and mounting the breast support article may assist the person making the product.

It will be understood from the foregoing and with respect to FIGS. 16, 17 and 18 that the breast support article comprising a supporting cup and angular side extensions are supported by a double thickness of fabric in the form of a band sewed around the perimeter of the cup and extension. The band starts at a point approximately three and one half inches beyond and below the point at which it engages the cup located over the center chest and is sewed along the edge of the cup to a point at the top of the cup where a wide elastic shoulder strap is attached as at A. The band continues down the side of the cup to a point just beyond the side cup extension where it turns on a substantially vertical band used as a hinge B, thence continues along the bottom of the cup to the starting point on the cup over the center chest. At that point it first engages the cup, thus forming a sling type support around the cup. The sling type support band around the bottom of the cup, and the side and center extensions are all concealed within a continuous and horizontal chest band of double ply soft fabric, starting at a point below the removed breast, its upper edge cut at an angle and joining the brassiere cup at a point just above the starting point of the lower support band on the cup, thence following the contours of the lower edge of the cup and up the side seam of the cup, thence continuing around the back and to the front starting point where it is secured with conventional and adjustable brassiere fasteners. Stitches are sewed through the chest band over the edges of the concealed hinge of the support band of the cup fixing it in place. The wide elastic shoulder strap is attached to the inside of the top cup band in front continuing over the shoulders and terminating at a point within the double ply of the back portion of the chest band and sewed in place. The three and one-half inch extension of the cup band con-

cealed in the front of the chest band is stitched in place at its end where it joins with the elastic of the brassiere fastener within the double ply at the start of the chest band.

The material shown in the center of FIG. 11 is Dacron polyester fiberfil.

I claim:

1. In a surgical mastectomy brassiere garment, a multiple ply of soft woven goods extending from the shoulders downward and both in front and in back of the wearer, the ply in front and in contact with the body of the wearer carrying means to simulate a breast mounted on the front surface of said ply, the body hugging garment with the attached breast form serving to remain in place and resist falling away from the wearer leans over forwardly.

2. In a surgical mastectomy brassiere garment of the type defined in claim 1, a multiple ply of soft woven goods extending from the shoulders downwardly and both in front and back of the wearer, the plies in front including one in contact with the body of the wearer carrying means to simulate a breast mounted on the front surface of the ply in contact with the skin of the wearer, the body hugging garment with the attached breast form serving to remain in place and resist falling away from the wearer's body when the wearer leans over forwardly.

3. In a surgical mastectomy brassiere garment of this type defined in claim 1, a multiple ply of soft woven goods extending from the shoulders downwardly and both in front and back of the wearer, the plies in front including one in contact with the body of the wearer carrying means to simulate a breast mounted on the front surface of the ply in contact with the skin of the wearer, the several plies being held together at shoulder straps and sides, the body hugging garment with the attached breast form serving to remain in place and resist falling away from the wearer's body when the wearer leans over forwardly.

4. In a surgical mastectomy brassiere garment of the type defined in claim 1 and extending from the shoulders downwardly, a double ply of soft woven goods adapted to extend down the front of the wearer and a ply of similar goods adapted to extend down the back of the wearer, the several plies being held together at shoulder straps, and means to simulate both right and left breasts secured to each other and to the front face of the rear ply down the front of the wearer, all of said plies being secured to each other at the right and left sides of said plies, the body hugging garment with the attached breast form serving to remain in place and resist falling away from the wearer's body when the wearer leans over forwardly.

5. In a garment for use after a single surgical mastectomy of the type defined in claim 1 and having a body hugging inner garment adapted to extend from the shoulders downwardly and formed of nylon tricot, a breast supporting article extending over a single breast, means for securing said supporting article over the area of the unremoved breast and having a band around the waist extending from an upper end adapted to be secured to a strap extending over the shoulder and said band extending downwardly diagonally across the chest line and terminating adjacent the opposite side of the thorax portion in a broadened strap serving as a belt, said strap leading from the upper end of the garment, thence passing over the shoulder and extending down the back and being secured to the band around the thorax at a point behind the back, the body hugging garment with the attached breast form serving to remain in place and resist falling away from the wearer's body when the wearer leans over forwardly.

6. In a garment for use after a single surgical mastectomy of the type defined in claim 1 and having a body hugging inner garment adapted to extend from the shoulders downwardly and formed of nylon tricot, a breast supporting article extending over a single breast, means

for securing said breast supporting article over the area of the unremoved breast, and having a band around the waist extending from an upper end adapted to be secured to a strap extending over the shoulder and said band extending downwardly diagonally across the chest line and terminating adjacent the opposite side of the thorax portion in a broadening strap serving as a belt, said strap leading from the upper end of the garment, thence passing over the shoulder and extending down the back and being secured to the band around the thorax at a point behind the back, said garment supporting a simulated breast form on the area of the removed breast and having a slit over the area of the unremoved breast to receive the breast support article, the body hugging garment with the attached breast form serving to remain in place and resist falling away from the wearer's body when the wearer leans over forwardly.

7. In a garment for use after a single surgical mastectomy having a body hugging inner garment adapted to extend from the wearer's shoulders downwardly and both in front and in back and formed of nylon tricot, a breast supporting article adapted to extend over a single breast, means for securing said breast supporting article over the area of the unremoved breast and having a band around the waist extending from an upper end adapted to be secured to a strap extending over the shoulder and said band extending downwardly diagonally across the chest line and terminating adjacent the opposite side of the thorax portion in a broadened strap serving as a belt, said strap leading from the upper end of the garment, thence passing over the shoulder and extending down the back and being secured to the band around the thorax at a point behind the back, said garment supporting a simulated breast form on the area of the removed breast and having a slit over the area of the unremoved breast to receive the breast support article, said garment being

5 secured to said breast simulating article above the area covered by the single remaining breast and said garment, and a breast form extending above the height of the upper edge of the regular breast and brassiere line, the body hugging garment with the attached breast form serving to remain in place and resist falling away from the wearer's body when the wearer leans over forwardly.

8. In a brassiere article for use after a single mastectomy of the type defined in claim 1, a breast supporting cup extending over a single breast and having a band 10 secured to said cup, said band extending from said upper end adapted to be secured to a strap extending over the shoulder and said band extending downwardly diagonally across the chest line and terminating adjacent the opposite side of a thorax portion of a broadened strap serving 15 as a belt, said cup being secured to said band along said diagonally extending portion, said strap leading from the upper end of the garment, thence passing over the shoulder and extending down the back and being secured to said band around the thorax at a point behind the back, the body hugging garment with the attached breast form serving to remain in place and resist falling away from the wearer's body when the wearer leans over forwardly.
